UNITED STATES PATENT OFFICE.

EWALD HÄHNEL, OF HOBOKEN, NEW JERSEY, ASSIGNOR TO CHARLES PALM
AND JULIUS FECHTELER, OF NEW YORK, N. Y.

DESIGN FOR ORNAMENTATION OF SEWING-MACHINES.

SPECIFICATION forming part of Design No. 12,547, dated October 25, 1881.

Application filed September 8, 1881. Term of patent 7 years.

To all whom it may concern:

Be it known that I, EWALD HÄHNEL, of Hoboken, in the county of Hudson and State of New Jersey, have invented a new and original Design for the Ornamentation of Sewing-Machines, of which the following is a specification.

This invention relates to a new and original design for the ornamentation of sewing-machines and other articles; and it consists in the novel grouping and configuration of figures, hereinafter more fully described.

In the accompanying illustrations Figures 1 and 2 are opposite views, in perspective, of a sewing-machine plate and arm having thereon my new design. Figs. 3 and 4 are top views, showing the ornamentation at the sides of the cloth-plate. Fig. 5 is a top view, showing the ornamentation at the front of the cloth-plate. Fig. 6 is a side view, showing the ornamentation of one side of the post that supports the sewing-machine arm; and Fig. 11 is a similar view, showing the ornamentation of the other side of said post. Fig. 7 is a side view of the ornamentation of the sewing-machine arm. Fig. 8 is a front view of the ornamentation for the front of the post of the sewing-machine arm. Figs. 9 and 10 show the ornamentation at the top of the sewing-machine arm.

The letter A represents the ornamentation for each side of the cloth-plate. It is a vine having many interlocking tendrils and carrying on proper stems oak-leaves and acorns, as shown. The oak-leaves are in part grouped in pairs, and in part in groups of three, thus producing a very beautiful effect.

The figure B represents the ornamentation directly in front of the figure A. It is a short nearly circular scroll, with outwardly and inwardly projecting tendrils carrying a cluster of three oak-leaves in its center and two oak-leaves at its outer portion, and series of acorns on the stems.

The figure C represents the ornamentation at the very front of the cloth-plate, and consists of a scroll carrying only three oak-leaves in its center and series of acorns.

The figure D shows the ornamentation for one of the sides of the post that carries the sewing-machine arm, and is a scroll carrying series of clusters of oak-leaves, nearly all being groups of three leaves with acorns interspersed, as shown.

The figure D' shows the ornamentation of the other side of said post, but has an additional curve, and terminates in a tendril which forms a sort of flat standard for the figure.

The figure E, which decorates the sides of the sewing-machine arm, is a long scroll containing series of oak-leaves and a band, on which the name of the machine (in this case "Hartford") is printed.

The figure F, which decorates the front of the post of the sewing-machine arm, is similar to the figure D, differing from it in that for 65 the clusters of three oak-leaves it substitutes mostly clusters of two, and where figure D has at its lower part a cluster of two oak-leaves figure F has three.

The figures G and H, which ornament the 70 top of the arm of the sewing-machine, are narrow scrolls having clusters of two oak-leaves and acorns, as shown.

I claim—

1. The design for the ornamentation of 75 sewing-machines, consisting of the figure A, substantially as shown.

2. The design for the ornamentation of 80 sewing-machines, consisting of the figure B, substantially as shown.

3. The design for the ornamentation of 85 sewing-machines, consisting of the figure C, substantially as shown.

4. The design for the ornamentation of 90 sewing-machines, consisting of the figures A, B, C, substantially as shown.

5. The design for the ornamentation of 95 sewing-machines, consisting of the figure D, substantially as shown.

6. The design for the ornamentation of 100 sewing-machines, consisting of the figure E, substantially as shown.

7. The design for the ornamentation of 105 sewing-machines, consisting of the figure F, substantially as shown.

8. The design for the ornamentation of 110 sewing-machines, consisting of the figures G and H, substantially as shown.

9. The design for the ornamentation of 115 sewing-machines, consisting of the figures A, B, C, D, E, F, G, and H, substantially as shown.

EWALD HÄHNEL.
